TRANSLUCENT LIGHT DIFFUSER PANEL

David M. Arrigoni, 4053 Freed Ave., San Jose, Calif.

Filed Nov. 16, 1964, Ser. No. 82,627

Term of patent 3½ years

(Cl. D48—16)

FIG. 1

FIG. 2

FIG. 6

FIG. 3

FIG. 4

FIG. 5

FIG. 7

FIG. 1 is a bottom plan view of a translucent light diffuser panel showing my new design.

FIG. 2 is a side view of the panel seen in FIG. 1 and shows the inclined side edge thereof.

FIG. 3 is an end view of the panel seen in FIG. 1 and shows the similarly inclined end edge thereof.

FIG. 4 is a sectional view seen along lines 4-4 of FIG. 1.

FIG. 5 is a sectional view seen along lines 5-5 of FIG. 1.

FIG. 6 is a perspective of the panel shown in FIG. 1 looking toward the right hand end of FIG. 1.

FIG. 7 is an enlarged fragmentary perspective view of a portion of the translucent light diffuser panel as seen in the area 7 of FIG. 1.

I claim:
The ornamental design for a translucent light diffuser panel, as shown and described.
